BUILDING BLOCK

Albert Joseph Schmitz, Milwaukee, Wis.

Application June 30, 1933, Serial No. 678,451

2 Claims. (Cl. 72—41)

The invention relates to building blocks and has for an object to provide a block having the characteristics of an offset at each end, the offset at one end extending from the upper portion of the block and the offset at the other end extending from the lower portion of the block, each offset overlapping an offset of an adjoining block of a series of blocks bonded together with mortar joints to form a course in a wall, the face of each block having mortar grooves therein dividing it into a plurality of panels simulating a wall constructed of smaller blocks or bricks.

Another object is to provide a building block formed with vertical through-openings which are designed to register with corresponding openings in superposed blocks to form flues for the reception of conducting means.

To the accomplishment of the foregoing, and such objects as may hereinafter appear, the invention consists in the features hereinafter described and sought to be defined by the claims, reference being had to the accompanying drawings forming a part hereof, and in which

Fig. 1 is a front elevation of a section of a wall constructed of blocks embodying the invention.

Fig. 2 is a sectional view taken on line 2—2 of Fig. 1;

Fig. 3 is a perspective view of adjoining blocks, one of which is shown in dotted lines, and

Figs. 4 and 5 are perspective views of filler blocks for use at wall and window openings.

In the drawing, the numeral 10 indicates a block provided at each end with offsets 12 of a width substantially the width of the block and a depth of substantially one half of the thickness of the block, the offset at one end extending from the upper portion of the block and the offset at the other end extending from the lower portion 40 of the block. The offset at each end of the block overlaps an offset of a companion block to which it is bonded by mortar to form a joint 15 when the blocks are laid in a course in the construction of a wall.

Each block is also formed with a plurality of openings 17 spaced from each other by a web 18, and extending through the block, the openings in one block registering with corresponding openings in a superposed block, in the several courses of the wall, the openings forming flues designed to receive piping or wiring 19 passing through the registering openings. The openings 17 have one side open, next to the offset at an end of the block, and the open side will be closed by the offset of the adjoining block, when the

blocks are laid end to end, and in courses, as will be obvious from an inspection of Figure 3 of the drawing.

At the ends of the courses where door or window frames 20 occur, blocks 21 of the form illustrated in Figure 4, and having L-shaped notches or recesses 23 at one end, are employed, and placed in the position shown in Figure 2; and a rectangular header block 22 is set across the offset portion of the next below block of the course as shown in Figures 1 and 2 of the drawing so as to close the open side of the through opening 23 of the adjacent block of the course as indicated in plan in Figure 2, and in side elevation in Figure 1, of the drawing. Also at the meeting ends of the two walls, which extend at an angle to each other, a rectangular block 22 is placed so that said block and the offset end portion of the adjacent block of one wall will close the open side of the through-opening in the wall block of the meeting end wall, as shown in Figure 2 of the drawing. It will be observed from the foregoing description and drawing that each wall consists of a number of blocks, each block 10 formed with offsets 13 and 14 at opposite ends, one offset 13 extending from the upper part of the block and the other offset 14 projecting from the lower part of the block at its opposite end, and that the blocks of each course are formed with a plurality of through openings 17 to receive conductor wires or piping 19, or both wires and piping, and also that one of the through openings 17 in each block 10 has one open side, closed by the offset 13 or 14 of the adjoining block in the same course. At the point in a course where window or door frames occur, at which point the open side of the through openings 23 in the two-part filler block 21, is closed by a substantially rectangular header block, or brick 22 (see Fig. 2).

At the corners of two walls, set substantially at right angles to each other, the projecting offset at the end of a block unit 10 may extend partially across the open side of a through-opening 17 formed in the unit and a rectangular shaped filler block or brick 22 may be placed so as to extend cross-wise of the open side of the through-opening 17 so that the open side of the opening 17 in the end block unit of one wall will be closed by the filler brick and by the projecting offset of the end block unit of the meeting wall as illustrated at the right hand side of Fig. 2, the filler block and projecting offset of one block unit lapping over the end offset of the end block unit of the other meeting wall as shown in the same figure of the drawing.

55

5 The side faces of each block unit are formed with longitudinally extending grooves and also with similar vertically extending grooves 11 intersecting each other so as to form or portray four panels on the exposed side face of the block unit, the panels appearing in break joints or 10 staggered relation to one another. The grooves may be filled or pointed up with mortar or other filling material, or left unfilled, and the wall 15 may thus be given the appearance of a brick wall of ordinary form, as previously stated. The panels 12 may have an ornamental surface or facing 16 formed by stone fragments embedded in the material of the panels in molding the blocks.

15 The offset end portions of the blocks in one course where they overlap the offset portions of the blocks of a superimposed course effect a substantial and efficient tying together of the several courses of the wall, tending to prevent sagging or settling of the walls, and also materially 20 reducing the time and labor in construction of a wall. The finished wall also has the appearance on its outer face of a bonded brick wall of ordinary construction, and in structural features is 25 stronger and more stable than a bonded brick wall as ordinarily constructed.

Other features of advantage will be obvious to and appreciated by the skilled in this particular art.

30 It will also be noted that by forming each block with an offset at opposite ends, one offset projecting from the upper portion of the block, and the offset at the opposite end projecting from the lower portion of the block, the blocks constituting each course may be laid in the manner 35 that bricks in an ordinary brick wall are laid, by simply laying one block on top of a block in a lower course, with a mortar bond between the superimposed blocks, and with the end offsets of one block overlapping the offset of the next adjoining block of the course without the necessity 40 of sliding a block longitudinally of the wall to bring the end offsets into overlapping relation to each other, thus effecting material saving in cost of time and mortar and labor.

45

It is to be understood that some features described may be used without others, and that changes can be made in details without departing from essential features of the invention as sought to be defined by the appended claims. 5

Having described my invention and set forth its merits what I claim is:

1. A wall comprising block units, placed end to end in courses, each unit formed with openings extending through the unit, one of said openings having an open side, and each unit formed at opposite ends with a projecting offset, the offset at one end projecting from the upper portion of the block and the offset at the opposite end projecting from the lower portion of the block, the offset 15 at one end overlapping the offset of an adjoining block, when the blocks are laid in courses, the offset at each end having a thickness equal substantially to one half the depth of the block and a width equal substantially to the width of 20 the block, the offset at one end of a block closing the open side of the through-opening in an adjoining block; additional blocks at the ends of the courses where window or door jambs occur, formed each with substantially L-shaped recesses forming an opening through said end blocks, and substantially rectangular shaped header blocks fitted between the door or window jamb and adjoining block formed with the L-shaped recesses. 30

2. A building block unit formed at opposite ends with an offset, the offset at one end projecting from the upper portion of the block and at the other end projecting from the lower portion of the block, each offset having a depth equal substantially to one half the maximum thickness of the block and a width equal substantially to the width of the block, the block being also formed with through-openings, at least one of which has an open side next to the projecting end offset, 40 adapted to be covered by the offset of an adjoining block when the blocks are laid in courses, whereby said through-openings register to provide flues for the reception of conducting means. 35
